UNITED STATES PATENT OFFICE

ALFRED E. HUDD, OF EVANSTON, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TRAIN STOP SYSTEM

Application filed July 11, 1929. Serial No. 377,418.

The present invention relates in general to train stop systems, but is particularly concerned with the provision of an intermittent magnetic inductive train stop system, and the component parts thereof.

Among the objects of the invention are: to provide improved types of trackway magnets for use in an intermittent inductive cab signal or train stop systems; to provide a new type of magnetic pickup relay or receiver, having armatures operable in any one of a plurality of selectable combinations, dependent on the characteristics of the magnetic field into which the relay is brought; to provide an improved mounting arrangement for the pickup relay or receiver; to provide novel circuit arrangements for controlling the condition of certain of the trackway magnets in accordance with traffic conditions; and to provide a system which may be readily used to give protection in single as well as double track systems.

The invention is disclosed in six sheets of drawings; sheet 1, comprising Figs. 1-3, shows a section of trackway equipped with the three types of trackway magnets used and the details of their construction.

Sheet 2, comprising Fig. 4, diagrammatically discloses the vehicle equipment used, and its relation to the trackway.

Sheets 3 and 4, comprising Figs. 5-9, show the pickup or receiver relay in detail and the mounting arrangement therefor.

Sheets 5 and 6, when arranged with sheet 6 to the right of sheet 5, show two track circuit arrangements; the one comprising Figs. 10 and 10A, and the other comprising Figs. 11 and 11A.

Referring now to Figs. 1-3, the constructional details of the trackway magnet assemblies A, B, and C will be described. The trackway magnet assembly A comprises two soft angle irons 12' and 12² held together by a shallow non-magnetic channel member 25, which is similar to the channel member 25' shown in Fig. 3, and is held in place with rivets such as 26. On the platform supported by the channel member 25 two notched wooden members 21' and 21² are placed up against the respective angle-irons 12' and 12². The mem-

bers 21' and 21² serve as separators for a number of permanent magnets 19. These magnets and the wooden members are held in place on the platform by a non-magnetic cover 16 which is bolted to the channel member 25 with a number of bolts 22. The assembly is held in place on the railroad tie 24, midway between the track rails, by lag screws 13' and 13². To afford further protection to the assembly a non-magnetic doubly inclined cover 17 is placed over the assembly and secured to the adjacent ties 23 and 28' by lag screws 18'-18⁴. The space between the respective magnets 19 allows room for possible warping of the magnets, and also prevents their losing their strength by the tendency of the stronger one to reduce to the power of the weaker one when in direct contact with each other. This is also the reason for providing a space between the ends of the magnets and the pole pieces 12' and 12².

The trackway magnet C is substantially like A, except that: the angle-irons 12³ and 12⁴ are longer; are farther separated by the channel member 25'; and have, at each side of the permanent magnet assembly electromagnets 28 and 29. The wooden members corresponding to 21' and 21² also hold the permanent magnets a greater distance from the pole-pieces 12³ and 12⁴. Due to the additional width of this assembly it is mounted on two ties, and is covered with a somewhat larger cover 17'.

The reason for providing a greater space between the ends of the permanent magnets of the assembly C, than is provided in the device A, is to enable the magnetic field set up by the permanent magnets of assembly C to be rendered ineffective by an extremely low current flow through the associated electromagnets 28 and 29.

The trackway magnet assembly B comprises two angle-iron pole pieces 12⁵ and 12⁶ like the corresponding parts of the assembly C. The assembly B, however, does not contain any permanent magnets, but instead, is provided with two pairs of electromagnets 27 and 28', respectively, connecting the pole pieces 12⁵ and 12⁶ through the medium of a third pole 30. The assembly is provided

with a protecting cover 17² substantially like the protecting covers of the assemblies A and C.

Referring now to Fig. 4, the vehicle equipment will be briefly described. The generator GEN, fuse box FB, and engineer's brake valve EBV are standard parts already existing on the locomotive, but are here shown merely to complete the disclosure of the system. The electro-pneumatic valve EPV, is of the usual type used in automatic train control systems, its main essential being that upon deenergization it permits the exhaust of air through its whistle W. For the purpose of reproducing the wayside signals in the cab, a panel 51 containing lamps G, Y and R is provided. A terminal box 50 is associated in the cab in the vicinity of the engineer's brake valve, and contains terminals for making the necessary connections between the generator, the cab signals, and the electro-pneumatic valve. This terminal box also contains a switch controlled by an acknowledging button AB, and a light control relay LCR, the functions of which will be described hereinafter. The cab equipment, having wires leading into the terminal box 50, is connected with the pickup or receiver relay R, through the medium of a junction box JB, located at an appropriate place between the engine and the tender. The automatic brake valve ABV may be of the same general type as the one disclosed in the Hudd application, Serial No. 296,652, filed August 1, 1928, and is designed to cause an automatic brake application to occur a predetermined period after the deenergization of an associated electro-pneumatic valve. The pickup or receiver relay R and the manner of mounting it is fully disclosed in the instant application.

Referring now to Figs. 5-7, the pickup or receiver relay R is contained in a non-magnetic box 101 having a water-tight cover 110. Mounted in the base of the box are six magnetic flux collector plates 102'-102⁶. These are held in place by bolts 113, and are insulated from the case 101 by the rubber washers 111 and 112, surrounding the bolts 113. Between the collector plates 102', 102², and 102³, and secured thereto are the respective assemblies 115' and 115². Likewise, between the collector plates 102⁴, 102⁵ and 102⁶, are positioned assemblies 115³ and 115⁴, respectively. The assembly 115' is held in place between the collector plates 102' and 102² by means of the double hole washers 131 and 131' and the associated screws 130 and 130'. The assembly 115' is also secured to the plates 102' and 102² through the medium of its pole-pieces 140 and 140'. These are firmly secured to the assembly 115' by means of rivets such as 141², and to the plates 102' and 102² by

screws 142. The assemblies 115²-115⁴ are held in place in the same manner as is the assembly 115'.

Referring now particularly to Figs. 6 and 7, further details of the construction of the assembly 115' will be described. In this connection it will be noted that Fig. 7 is an enlarged side view of the assembly 115', with the pole piece 140 omitted for the sake of clearness. Secured to the plate 115' is an armature and terminal support 126 having associated ears through which the armature pin 123 passes to hold the armature 133 in place. Extending upwardly from the armature 133 is an auxiliary armature member 122, securedly riveted in place by the rivets 134. This upwardly extending portion 122 serves as an armature for the electro-magnet 141, shown in Fig. 5. At the free end of the armature a contact member 125 is firmly held in a notched insulating member 124. A stud 118 extending upwardly from the armature support 126 carries a two-conductor terminal having conductor-connecting ears 119 and 120. This terminal is insulated from the stud 118 by means of a sleeve 132, and insulating washers 127 and 128, clearly shown in Fig. 6. A flexible connection 121 extends between the contact member 125 and the terminal 120. To the rear of the armature support 126 is mounted a permanent magnet 143, held in place by a bracket 116 and the associated screws 117. This permanent magnet polarizes the armature 133. The remaining assemblies 115²-115⁴ are like the assembly 115', with the exception that the armature extension 122 is omitted in the case of assemblies 115³ and 115⁴. Secured to the collector plate 102², by means of brackets 145 and 145' are electro-magnets 141 and 141'. These magnets are for the purpose of attracting the associated armatures through the medium of their pole-piece extensions 122. Secured to the pole piece 140' under magnet 141' is a contact spring 146 for co-operation with the contacts of the contact element 125. Like contact springs are provided on the pole pieces of the other assemblies which cooperate with their respective armatures. Mounted on the collector plate 102² is a terminal strip 150, where the necessary connections from the armatures and associated contacts are terminated. The necessary connections to the cab equipment are brought through an opening 151.

Referring now to Figs. 8 and 9, the apparatus by means of which the receiver R is suspended from a locomotive tender will be described. The angle-irons 155 and 156 are secured to an appropriate place on the locomotive tender, and the receiver R is suspended therefrom through the medium of four bars 157, 158'-158³ (158³ not shown). The bar 157 is secured to the threaded portion 165 of the receiver by a shouldered cap

screw 161, and to the angle-iron 155 by means of a bolt 159. A washer 162 serves as a spacer between 157 and 155, while a spring 160, substantially entirely compressed when the nut 163 is drawn up, serves to assist in firmly holding the bar 157 tightly compressed against the washer 162. The remaining bars 158'-158³, are mounted in the same manner.

In perforations extending through the upper portion of bar 157 and through the angle-iron 155 are provided hard rubber bushings 166 and 166' with metal tubes 167 and 167' within the bushings. Passing through these tubes is a wire 200, labeled in Fig. 4 as the detector loop. With the manner of mounting the receiver described, and with the arrangement of conductor 200 passing through tubes 167 and 167', if the receiver encounters a rigid object it will be elevated in its entirety, 20 the bolts such as 159 and 161 serving as pivots. When this occurs, a shearing action will take place between the tubes 167 and 167', severing the conductor 200 and initiating an automatic brake application in a manner 25 which will subsequently be made clear.

Referring now to Figs. 10 and 10A, with Fig. 10A placed to the right of Fig. 10, the track circuits shown therein, and the influence thereon by the presence of the vehicles V¹ and V², will be described. In block G the vehicle V² is shunting track battery TB⁴ from its track relay T³, and this relay is consequently in its deenergized condition. The relay T³, at its inner and middle armatures 30 has broken the circuit of line relays L1³ and L2³, and at its outer armature has completed a circuit for the lamp R of the signal S³. This circuit extends from the positive terminal of the battery GB, through the contact 35 and armature of the line relay L1³, the lower armature and lower contact of the track relay T³, through the lamp R of the signal S³ to the negative terminal of the battery GB. Neither of the relays Y³ or G³ is energized 40 at this time, and, consequently, there is no current flow in either of the trackway devices C³ or B³. A train approaching the block G, therefore, will have its train control equipment influenced only by the permanent magnets of C³ and by the permanent magnets comprising the trackway device A³.

Referring now particularly to the train control equipment at the exit end of block E and to the signalling equipment at the entrance end of block F, the influence of the vehicle V² on this equipment will be considered. It will be noted that the line relay L2² is deenergized. This occurred when the vehicle V² interrupted its circuit by dropping the track relay T² upon entering the block F, and has remained deenergized, because a second point in its circuit was opened when the vehicle V² entered the block G, the circuit for relay L2² including in series, the line relay L1³. The circuit of these relays

extends from the positive terminal of line battery LB³, through the upper armature and contact of the track relay T³, the line relay L1³, the line conductor 201³, through the middle armature and contact of the track relay T², the winding of the line relay L2², and the conductor 202³ to the negative terminal of the line battery LB³. The line relay L2² at its armature opens a point in the operating circuit of lamp G of the signal S² and of the associated relay G², and closes a point in the operating circuit of the lamp Y of the signal S², and of the associated relay Y². The circuit to the relay Y² and the lamp Y of S² is not closed at this time, however, owing to the energized condition of the line relay L1², this relay being energized over a circuit similar to the one traced through line relays L2² and L1³.

There is no current flow through the trackway element C² or through the element B² owing to the deenergized condition of both relays Y² and G² and, accordingly, the trackway devices at the exit of block E are for the time being in exactly the same condition as those located at the exit of block F. The influence of the vehicle V² on the train control equipment at the exit end of block E so far has only been to the extent of preparing a circuit for relay Y². The vehicle V¹, however, in block D has caused the deenergization of line relay L1¹, thereby causing the lamp G of the signal S¹ and the associated relay G¹ to be energized. The circuit for the lamp G of signal S¹ and relay G¹ extends from the positive terminal of battery EB through the contact and armature of relay L1¹, the lower armature of relay T¹, and its upper contact, the armature and upper contact of relay L2¹, through the lamp G of signal S¹ and relay G¹ in multiple to the negative terminal of the battery EB. The relay G¹, at its lower armature has completed a circuit through the windings of the trackway device C¹, and at its middle and upper armatures has completed a circuit through the windings of the trackway magnet B¹. The circuit through the trackway magnet C¹ extends from the positive terminal of the battery EB, through the lower contact and armature of relay G¹, the conductor 204¹, the windings of the magnet C¹, conductor 205¹, and back to the negative terminal of the battery EB. Owing to the current flow through the electromagnet of the device C¹, the magnetic field normally set up by the permanent magnets associated therewith is rendered ineffective. The circuit for the trackway magnet B¹ extends from the positive terminal of the battery EB, through the middle armature and contact of the relay G¹, conductor 206¹, the upper and lower windings of B¹, conductor 207¹, and through the upper contact and armature of relay G¹ to the negative terminal of the battery EB. The direction of current

flow through the windings of B' is such that its upper and lower pole-pieces are of north polarity, whereas the middle pole is of south polarity, thereby setting up two magnetic fields, one from the upper to the middle and the other from the lower to the middle pole-piece of the trackway device B' .

The condition of the vehicle equipment shown in Fig. 4 will now be described, after which it will be assumed that this equipment is on the vehicle V' which is travelling toward the vehicle V^2 . The vehicle equipment is in the condition which it assumes upon passing a signal at "clear". The armatures 125^1-125^4 are all attracted against their inner pole-pieces, and, because of this, circuits exist for the cab signal G , the light control relay LCR , and the electro-pneumatic valve EPV , respectively.

The circuit of cab signal G extends from the negative terminal of the generator GEN , through the upper fuse of fuse-box FB , conductor 71 , terminal 9 of terminal box 50 , jumper 85 to terminal 8 , jumper 87 to terminal 5 , the conductor 78 , lamp G , conductor 77 , terminal 4 , conductor 63 , terminal 4 of junction-box JB , conductor 56 , the inner contact and armature 125^3 , conductor 86 , armature 125^4 and its inner contact, conductor 54 , terminal 1 of JB , the detector loop, terminal 2 of JB , conductor 61 , terminal 2 of 50 , conductor 74 , the acknowledging switch, conductor 73 , terminal 1 , the lower fuse of fuse-box FB to the positive terminal of the generator GEN .

The winding 52 of the light control relay LCR , by means of the conductors 80 and 81 , is connected in multiple with the lamp G and is, therefore, energized whenever a circuit exists for the lamp. The relay LCR , and the electro-pneumatic valve EPV extends from negative potential on terminal 9 of 50 , over conductor 70 , through EPV , conductor 68 , terminal 12 of 50 , jumper 67 , terminal 11 , conductor 66 , terminal 5 of JB , conductor 60 , armature 125^1 and its inner contact, inner contact and armature 125^2 , conductor 57 , to positive generator supplied to the terminal 1 of JB by way of the detector loop, terminal 2 , the conductor 61 , terminal 2 of 50 , and the acknowledging switch. It may be well to call attention to the fact that all apparatus on the vehicle must obtain the positive current through the acknowledging switch and through the detector loop, respectively, and, therefore, if the detector loop becomes broken an automatic brake application will take place.

The effect on the vehicle equipment, as the vehicle V' advances will now be explained.

Since, as previously mentioned, the trackway element C' has its electromagnet winding energized at this time, the permanent magnets thereof are rendered ineffective to

influence the armatures of the receiver R when the same passes thereover.

When, however, the receiver is brought into the inductive field of the trackway device A' , the collector plates 102^1 and 102^4 are brought into the inductive influence of the north pole, and collector plates 102^3 and 102^6 are brought into the inductive field of the south pole of the trackway device A' . Since the armatures 125^1 and 125^3 are already of north polarity, because of the presence of the associated polarizing magnets 84^1 and 84^3 , there will be no tendency for these armatures to move. The armatures 125^2 and 125^4 , also of north polarity, because of the presence of polarizing magnets 84^2 and 84^4 , will, however, be attracted to their outer pole pieces, because of the stronger attractive effect produced therein by the magnetic flux picked up by the collector plates 102^3 and 102^6 from the south pole of the magnets of the trackway device A' . After the receiver passes out of the inductive field of the trackway device A' the armatures 125^2 and 125^4 remain in their operated position owing to the natural attraction of the armature to the nearest pole-piece, because of the presence of the polarizing magnets 84^2 and 84^4 .

The armature 125^4 , in operating, opens the traced circuit for the lamp G and relay LCR , causing that lamp to be extinguished, and the relay to drop its armature. The armature 125^2 also, at its lower contact closes a point in the circuit of lamp Y , which will be traced later. The armature 125^2 , in operating, opens the traced circuit of the electro-pneumatic valve EPV which becomes deenergized and permits air to exhaust through the whistle W . The dropping of the armature of relay LCR prepares a point in the circuit of lamp R , which will also be traced later.

The opening through the whistle W is of such a size that approximately six seconds must elapse before sufficient air has passed therethrough to permit the operation of the automatic brake valve ABV . Before much of this time expires, however, the receiver R in the vehicle V' passes through the inductive field of the trackway device B' , which, as previously explained, is so energized that its upper and lower pole pieces are of north polarity, whereas its center pole piece is of south polarity. As the receiver R passes through the magnetic field set up by the trackway device B' the collector plates 102^1 , 102^4 , 102^3 and 102^6 collect magnetic flux of north polarity from the upper and lower pole pieces of B' , while the collector plates 102^2 and 102^5 collect magnetic flux of south polarity from the middle pole-piece of B' . The magnetism induced in the pole pieces of collector plates 102^1 and 102^4 being of the same polarity as that normally existing in armatures 125^1 and 125^3 , because of the presence of the polarizing magnet, tends to make

- the armatures remain in engagement with their inner pole-pieces, while the magnetic flux induced in the pole-pieces of collector plates 102² and 102⁵ is of south polarity.
- 5 This causes all armatures 125'-125⁴ to tend to be drawn towards their inner pole-pieces; while in the case of the collector plates 102³ and 102⁶, since the magnetic flux induced therein is of north polarity, the pole-pieces of
- 10 these collector plates tend to oppose or push away the armatures 125² and 125⁴, with the result that these armatures are restored to their initial position, causing the circuits for lamp G, the winding 52 of relay LCR and
- 15 valve EPV to be reestablished automatically. The momentary operation of the whistle W and the momentary extinguishing of lamp G simply serve to inform the enginemen that they have passed a signal at "clear".
- 20 As the vehicle V' enters the block E, the track relay T' is shunted out by the axle of the vehicle, and accordingly, drops its armature. Like in the case of the track relay T³, the track relay T' at its upper armature in-
- 25 terrupts a second point in the circuit of line relay L1', preventing that relay from re-energizing until the vehicle V' is clear of the block E; at its middle armature it interrupts the circuit of line relays L2' and L1² and at
- 30 its lower armature it interrupts the multiple circuit of the lamp G of signal S' and of relay G', and closes a circuit for the lamp R of signal S'. The circuit of the red lamp R of signal S' extends from the positive ter-
- 35 minal of the battery EB, through the contact and armature of L1', the lower armature and lower contact of T', through the lamp R, conductor 203', and back to the negative terminal of battery EB.
- 40 The dropping of the armature of relay L1² when the vehicle V' enters block E completes a circuit for the lamp Y of signal S². This circuit extends from the positive terminal of the battery FB, through the contact and
- 45 armature of L1², the lower armature and upper contact of track relay T², the armature and lower contact of L2², and through the relay Y² and lamp Y of signal S² in multiple to the negative terminal of a battery FB.
- 50 The lamp Y of signal S², therefore, lights up upon the entry of the vehicle V' into the block E. The relay Y², upon becoming energized, completes a circuit from the positive terminal of the battery FB, through its lower
- 55 contact and armature, through the conductor 204², and through the return conductor 205² to the negative terminal of the battery FB, thereby rendering the permanent magnets of the trackway device C² ineffective to in-
- 60 fluence the receiver R. The relay Y² also, at its middle and upper armature, completes a circuit through the trackway device B², ex-
- 65 tends from the positive terminal of the battery FB, through its middle armature and contact, the conductor 207², and through

the lower and upper windings, respectively, of the trackway device B², the conductor 206², and the upper contact and armature to the negative terminal of the battery FB. It should be noted at this time that the current flow through the trackway device B² is in the direction reverse to that in which current passed through the trackway device B' while the vehicle V' was passing thereover.

As the vehicle V' passes over the trackway magnets A², the armatures 125² and 125⁴ of the receiver R are operated, as in the case when the receiver passed over the trackway device A', again positioning armatures 125² and 125⁴ against their outside pole-pieces.

An instant later, as the receiver passes over the trackway device B², the armatures 125¹ and 125³ are also moved into engagement with their outside pole-pieces. This occurs, be-

cause the polarity of the upper and lower poles of the trackway device B² are now of south polarity and, therefore, attract the armatures, all of which are of north polarity. This at-

tractive action toward the outer pole pieces is further assisted by the magnetic flux of north polarity transmitted to the inner pole-pieces of collector plates 102² and 102⁵ from the middle pole-piece of the trackway device B².

The operation of armature 125¹ simply interrupts a second point in the circuit of the electro-pneumatic valve EPV, while the armature 125³, in addition to opening a second point in the circuit of the cab signal lamp G, at its upper contact, completes a circuit for the cab signal lamp Y and for the winding 52' of relay LCR. The lighting up of lamp Y and the continuous operation of the whistle W serves to inform the enginemen that a signal has been passed at "caution" and acknowledgement must immediately be

made to prevent the occurrence of an automatic brake application. The circuit for the cab signal lamp Y extends from the negative terminal of the generator GEN, over the previously traced circuit to conductor 78, through the lamp Y, terminal 7 of terminal box 50, terminal 7 of junction box JB, conductor 53, the lower contact and armature

125⁴, conductor 86, armature 125³ and its up-

per contact, conductor 55, terminal 1 of the junction box JB, the detector loop, and over the previously traced circuit to the positive terminal of the generator. A branch circuit, in multiple with that traced for the lamp Y, extends from terminal 7 of the terminal box

50, through the winding 52' of relay LCR, and back to the negative terminal of the generator by way of terminal 9, and maintains the relay LCR energized when the lamp Y is

125² lighted.

It will be assumed that the change in signal is acknowledged within the time allowed, and therefore, no automatic brake application takes place. To acknowledge, an engineman simply momentarily depresses the

acknowledging button AB. While the acknowledging button is depressed, positive current is removed from conductor 74, thereby extinguishing lamp Y, deenergizing relay LCR, and opening a second point in the circuit of EPV. The button AB must, therefore, be restored to bring about the reenergization of the electro-pneumatic valve EPV. The pressing of the acknowledging button 10 causes a circuit to be completed for restoring armatures 125' and 125² into engagement with their inner pole-pieces. This circuit extends from the negative terminal of the generator, over the previously traced path to terminal 8 in the terminal-box 50, conductor 65, terminal 6 in junction box JB, conductor 58, through the armature restoring windings 141 and 141' in series, conductor 59, terminal 3 of JB, conductor 62, the terminal 3 of the terminal box 50, the conductor 75, the acknowledging switch to the conductor 73 and positive generator. The current flow through the windings 141 and 141' causes the pole-pieces thereof to attract the armatures 125' and 125² back into their normal position. Upon the restoration of the acknowledging button AB the previously traced circuits for the lamp Y, relay LCR, and electro-pneumatic valve EPV are again reestablished. It will be noted that there is no manually controlled means for actuating the armatures 125³ and 125⁴ and, therefore, the only way of changing the lamp signal indication in the cab is by picking up influences from the track-way to do so.

As the vehicle V' enters into block F the track relay T² is shunted out and, accordingly, drops its armatures. This relay at its lower armature opens the circuit of lamp Y of signal S² and completes the circuit of the lamp R of signal S²; at its upper armature opens a second point in the circuit of line relays L1² and L2²; and at its middle armature opens a second point in the circuit of relays L2² and L1³.

As the vehicle V' clears the block E the track relay T' again becomes energized, at its upper armature again completes the operating circuit of line relay L1', at its middle armature closes a point in the circuit of line relays L2' and L1², and at its lower armature interrupts the circuit of lamp R of signal S' and prepares a circuit for the lamp Y of signal S'. The energization of line relay L1', however, prevents the lighting up of lamp Y of signal S' until a vehicle enters the block D, as previously described. Since the lamp R of the signal S² is lighted, lamps Y and G of S² and relays Y² and G² are deenergized. Consequently, as previously brought out, there is now no current flow through the electromagnets of the trackway devices C² and B².

Attention is now called to the fact, that as the receiver R is approaching the trackway

device C³, with the yellow lamp Y in the cab lighted, its armatures 125' and armature 125² are in their normal position, as shown, while the armatures 125³ and 125⁴ are both in engagement with their outside pole pieces. As the receiver comes into the inductive field of the trackway device C³, which has its electromagnet deenergized at this time, the inductor C³ functions in the same manner as a permanent magnet trackway device such as A', A², or A³; accordingly, the north polarity induced into the collector plate 102⁴ causes the armature 125³ to be repelled and moved into engagement with its inner pole-piece, thereby interrupting the traced circuits of lamp Y and relay LCR and completing a circuit for cab signal R, while the south polarity induced in the pole piece of the collector plate 102³ attracts the armature 125² to its outside pole-piece, to again initiate a brake application by interrupting the traced circuit for the electro-pneumatic valve. To avoid an automatic brake application an engineman must again acknowledge to restore the armature 125² in the manner formerly described. Upon the restoration of the armature 125² a circuit for the lamp R in the vehicle cab in multiple with the circuit of the electro-pneumatic valve EPV is completed. This circuit extends from the negative terminal of the generator GEN over the circuit traced to conductor 78, through the lamp R, conductor 79, the terminal 10 in the terminal box 50, the back contact and armature of relay LCR, the conductor 69, to the terminal 12 of the terminal box 50, conductor 67, terminal 11, conductor 66, terminal 5 of JB, conductor 60, armature 125', conductor 82, armature 125², conductor 57, terminal 1 of JB, loop 200, terminal 2 of JB, conductor 61, terminal 2 of the terminal box, conductor 74, through AB, conductor 73, and conductor 72 to the positive terminal of the generator GEN.

The lighted lamp R in the vehicle cab advises the engineman that they have arrived within braking distance of an occupied block and must, therefore, have the vehicle in full control prepared to stop at the entrance to block G.

When the receiver R passes over the track-way device A³ the armature 125² is again actuated to again initiate a brake application. Since at this time there is no current flow through the trackway device B³ an engineman must again acknowledge to prevent an automatic brake application.

If a vehicle enters a block at "clear" or "stop" and then backs over the B and A inductors of the block just entered the receiver will respond to the A inductor, extinguish the existing cab signal, and initiate a brake application, and the usual acknowledgment must be made, which will be followed by the lighting of the lamp R. If, however, a vehicle backs out of a block at

"caution" the B inductor will initiate a brake application by actuating armatures 125' and 125² and acknowledgment will be necessary to restore these armatures. As the receiver R passes over the A inductor, however, the lamp Y will be extinguished, and upon acknowledgment, the lamp R lighted.

Referring now to Figs. 11 and 11A, the application of the invention applied to a railway signalling circuit of the "wireless" type, and special features provided at the entrance to sidings and cross-overs will be described. The signal S⁸ at the cross-over X in block L is interlocked with the signal S⁷ in the usual manner, and the circuit arrangements are such that when the block L is occupied or when the signal S⁸ is in proceed position the track battery of block L will be shunted from the associated track relay T⁷. Since in the example given the signal S⁸ is in proceed position the track relay T⁷ is deenergized. This relay, at its upper and middle neutral armatures and their lower contacts connects the battery LB across the rails of block K in the proper direction to cause the track relay T⁶ at the entrance to that block to move its polarized armature to the right, but owing to the presence of vehicle V⁴ in that block the track relay T⁶ is deenergized. The track relay T⁷ at its lower neutral armature interrupts the normally established circuit extending over conductors 304³, 305³, 304⁴ and 305⁴ to the trackway devices C⁷ and C⁸, respectively, and at its lower neutral and polarized armature disconnects the battery IB³ from the pole changing relay P⁴, through the contacts of which, the trackway device B⁷ is supplied with current through the lower neutral armature of the track relay T⁷ in a direction dependent on the energized and deenergized condition of the pole-changing relay P⁴.

It will be assumed for the moment that the vehicle V⁴ is equipped with the vehicle equipment such as shown in Fig. 4, and further that the vehicle V⁴ passes from the block K into block L. As the receiver R passes over the trackway device C⁷, (placed at braking distance from the exit of the block) the vehicle receiver relay armatures will be operated in the same manner as described when passing over the trackway inductor C³. Shortly after the acknowledgment is made the receiver will pass over trackway device C⁸ and a second acknowledgment will consequently have to be made. The passing over the permanent magnet trackway inductor A⁷ will require a third acknowledgment of the engineman. These warnings come in fairly close succession and serve to inform the enginemen that they are approaching a cross-over at which the signal is set at stop, and that they should, therefore, proceed with extreme caution.

As previously stated, owing to the presence

of vehicle V⁴ in block K, the associated track relay T⁶ is deenergized. This relay, at its upper two armatures and their lower contacts connects the battery KB across the rails of block J in such a manner that the current flow to the track relay T⁵ is energized in the proper direction to cause its polarized armature to swing to the right; at its next to bottom neutral armature opens the circuit of relay 310; and at its lowermost neutral armature completes a circuit for the thermo-relay 320. The relay 310, in dropping its armature, opens a second point in a circuit for the electro-magnetic switch lock 325. After a definite period the thermo relay 320 again closes a circuit for relay 310. This arrangement is provided to prevent the associated siding being unlocked and connected with the main line by operation of button 315 while the section between the siding and the entrance end of block K is occupied, or at least until sufficient time has elapsed to allow the vehicle V⁴ to have approached near the vicinity of the siding. The polarized armature of the track relay T⁶ serves to open the circuit of the trackway device C⁶ to cause it to function in the same manner as did the trackway device C³ under the same traffic condition. The track relay T⁶ also at its two upper armatures connects the battery KB across the rails of block J in the proper direction to cause the track relay T⁵ to move its polarized armature to the right. The track relay T⁵ at its upper armatures and their upper contacts in turn supplies current from the battery JB to the rails of block I in the proper direction to cause the track relay T⁴ to move its polarized armature to the left. The track relay T⁵ also, at its lower neutral armature, completes a circuit by way of conductor 305', the battery IB², and conductor 304' for the trackway device C⁵, rendering the permanent magnets thereof ineffective to influence the receiver relay of an approaching vehicle. The relay T⁵ also, at its lower neutral armature, completes a circuit from the positive terminal of battery IB², through the lower contact and armature of the pole changing relay P², the conductor 307², the lower and upper windings of the trackway device B⁵, conductor 306², the upper armature and lower contact of relay P², and back to the negative terminal of the battery IB². The current flow through the trackway device B⁵ is in the same direction as that traced through the trackway device B² and, therefore, will have a like influence on the receiver of a vehicle passing thereover.

The trackway relay T⁴ completes circuits similar to those traced through the contacts of the track relay T⁵, except that the relay T⁴ has its polarized armature moved to the left. In consequence of this difference a circuit is completed from the positive terminal of bat-

tery IB' , through the contact and lower neutral armature of T^4 , the polarized armature of this relay, conductor 308', through the pole changing relay P' , back to the negative terminal of battery IB' . The pole-changing relay P' , therefore, changes the direction of current flow to the trackway device B^4 , causing it to be energized in the same manner as was the corresponding trackway device B' at the exit end of block D .

Since the condition of the trackway devices of blocks H , I , J , and K are identical to those encountered by the vehicle V' in passing over the blocks D , E , F , and into block G , a description of the controlling conditions brought about in the vehicle V^3 in passing over blocks H , I , and J will be unnecessary.

What is claimed is:

1. In a relay operable by magnetic induction, a plurality of armatures, magnetic flux collecting plates individual to each armature, and other magnetic flux collecting plates each common to two of said armatures, all said flux collecting plates being selectively magnetically influenced to selectively actuate one or a combination of said armatures.

2. In a relay operable by magnetic induction, four armatures, and a plurality of elements associated with each armature which provide magnetic paths for selectively operating said armatures.

3. In a relay operable by magnetic induction, a plurality of magnetic flux collector plates each having but one-pole-piece, a second plurality of magnetic flux collector plates each having but two pole-pieces, a plurality of armatures associated with said pole-pieces, one armature in each instance being common to the pole-piece of one of the first collector plates and to a pole-piece of one of the second collector plates.

4. In a receiver relay for use in picking up magnetic influences transmitted from apparatus along a trackway, three magnetic flux collector plates, a pole-piece on each of two of said plates and two pole-pieces on the third of said plates, and polarized armatures between said pole-pieces selectively operable by magnetic flux transmitted to said collector plates.

5. In a receiver relay, a moisture-proof casing of non-ferrous metal, a set of six magnetic flux collector plates in said casing arranged in two rows of three each, and a polarized armature assembly between the flux collector plates of each row.

6. In a train control or cab signal system, a receiver relay, and means for suspending said relay from a vehicle comprising a plurality of vertical bars, each rotatably connected to the receiver and vehicle, respectively, and spring means associated with the connections between the vertical bars and the vehicle for preventing any free rotary motion of said bars.

7. In a train control system, a vehicle carried relay for inductively picking up magnetic impulses transmitted to it from points along the trackway, armatures on said relay operative responsive to a magnetic impulse of one polarity for initiating a brake application and changing a cab signal indication respectively, and other armatures on said relay operative to produce the same functions in case the impulse received is of the opposite polarity.

8. In a train control system, vehicle equipment including three lamp signals, a relay having a plurality of armatures operable by magnetic flux transmitted from apparatus placed intermittently along the trackway, circuits for two of said signals including a source of operating current and certain of the armatures of said relay, another relay having a first winding in multiple with one of said two signals and having a second winding in multiple with the second of said two signals, and a circuit for said third signal including said armatures and an armature of said second relay.

9. In a magnetic device, a pair of armatures, a magnetic flux collecting element having pole-pieces for attracting said armatures, and having other magnetic flux collecting elements with pole-pieces for also attracting said armatures.

10. In a magnetic device, a pair of armatures, associated elements for operating said armatures, means transiently associated with said elements for causing one of said elements to tend to attract both of said armatures under one condition and to tend to repel both of said armatures when in another condition, and other means transiently associated with certain of said elements for causing one of said elements to tend to attract one of said armatures and another of said elements to tend to repel the other of said armatures.

11. In a relay operable by magnetic induction, a plurality of armatures selectively operable in accordance with the magnetic condition of the surrounding atmosphere, magnetic flux collecting plates included in magnetic circuits individual to their associated armatures when certain magnetic conditions exist, and other magnetic flux collecting plates common to said armatures and included in the magnetic circuits of said armatures irrespective of the magnetic condition encountered.

12. In a relay directly operable by magnetism picked-up as it passes through a magnetic field, a plurality of armatures, a plurality of flux collecting plates, separate magnetic circuits including said flux collector plates for actuating said armatures in certain instances, and a magnetic circuit including all of said flux collecting plates in series in other instances, to actuate the relay.

13. I a relay, a pair of armatures, magnetic flux collecting plates having pole-pieces for actuating one or the other of said armatures when the plates are brought within a magnetic field, means associated with said armatures for preventing one or the other of said armatures from operating depending upon the polarity of the magnetic field, and means including another flux collecting plate cooperative with said first collecting plates for restoring either actuated armature.

14. In a vehicle equipment of a cab signal and train control system, a relay having a plurality of armatures operable by magnetic flux transmitted from apparatus placed intermittently along the trackway; a plurality of signal control circuits, one of which includes a pair of said armatures in one position, another of which includes said armatures in an alternative position, and a third of which includes a second pair of said armatures; a circuit including a brake application initiating device and the latter pair of armatures in series, and manually operable means 25 for re-establishing said latter circuits only.

15. In a vehicle equipment of a cab signal and train control system, a relay having a plurality of armatures operable by magnetic flux transmitted from apparatus placed intermittently along the trackway; a plurality of signal control circuits, one of which includes a pair of said armatures in one position, another of which includes said armatures in an alternative position, and a third of which includes a second pair of said armatures; a circuit including a brake application initiating device and the latter pair of armatures in series, and manually operable means for re-establishing one or both of said 40 latter circuits only, depending on the condition of the other signal circuits.

In witness whereof, I hereunto subscribe my name this 8th day of July, A. D. 1929.

ALFRED E. HUDD.
